WILFRED FOURNESS, OF PASADENA, CALIFORNIA, ASSIGNOR, BY MESNE ASSIGNMENTS, TO THE FOURNESS DEVELOPMENT CORPORATION OF NEW YORK, N. Y., A CORPORATION OF NEW YORK

CONTROL SYSTEM

Application filed July 28, 1926. Serial No. 125,460.

This invention relates to an electrical control system, and especially to one that is adapted to control the operation of a mechanical refrigerating plant.

5 In the usual type of mechanical refrigeration, use is made of a fluid refrigerant, which absorbs heat as it is allowed to expand under low pressure, in an expansion chamber or coil. Mechanical work can then be performed on 10 the fluid after it is fully expanded and removed from the expansion space, to compress it and thereafter to abstract its heat content. It can then be recondensed, and passed again to the expansion space to repeat 15 the cycle.

Since the system is a closed one, utilizing the same refrigerant over and over again, it is evident that the compression and condensation of a portion of the refrigerant has 20 the effect of reducing the pressure in the expansion space which is of course connected to the intake of the compressor. This partial vacuum so produced, ensures rapid expansion and consequent rapid cooling. In 25 small installations, such as in connection with domestic ice boxes or with store display cases, the operation of the compressor to maintain a low pressure need be only intermittent, there being a sufficient vacuum maintained 30 for an appreciable time even when the compressor is shut down.

It has been proposed to operate the compressor automatically in accordance with the pressure existing in the expansion space; but 35 such prior schemes are cumbersome and expensive. It is accordingly one of the objects of my invention to provide a compressor control that is simple and reliable.

In connection with such schemes for controlling 40 the compressor, it is obviously advantageous to arrange the mechanism so that it will not be set into operation for every slight variation in pressure, but instead, there should be limits of pressure between which 45 the control mechanism is inactive. It is thus

another object of my invention to make it possible not only to provide limits of pressure between which the control is inactive, but also to adjust these limits.

In order to provide such a control system, 50 a pressure responsive device must be used; and it is another object of my invention to provide a novel, simple, and rugged device of this character.

My invention possesses many other advantages, and has other objects which may be made more easily apparent from a consideration of one embodiment of my invention. For this purpose I have shown a form in the drawings accompanying and forming part 55 of the present specification. I shall now proceed to describe this form in detail, which illustrates the general principles of my invention; but it is to be understood that this detailed description is not to be taken in a 60 limiting sense, since the scope of my invention is best defined by the appended claims. 65

Referring to the drawings:

Fig. 1 is a side elevation, with some of the parts broken away, of a pressure responsive 70 device for controlling the compressor in the refrigerating system;

Fig. 2 is a top plan view thereof;

Fig. 3 is a reduced size fragmentary side elevation similar to Fig. 1 and showing an 75 alternate position of the apparatus;

Fig. 4 is a sectional detail taken along plane 4-4 of Fig. 2; and

Fig. 5 is a fragmentary view taken along plane 5-5 of Fig. 1. 80

The compressor of a refrigerating system can be controlled so as to start operation only when the pressure in an expansion space reaches a high value. In this way the pressure of the refrigerant is reduced to the desired limits. 85

In order to control the operation of the compressor in response to pressure variations in the expansion chamber, I provide a device 90 which serves to control the energizing cir-

cuits for the motor that operates the compressor.

In this device, I provide a flexible chamber 28, the shape of which alters upon variations in pressure, the alteration being utilized to provide a controlling function. The chamber 28 is preferably made from thin copper folded into accordion or bellows form, whereby a large longitudinal expansion and contraction of the chamber can be effected even for comparatively small variations in the gas pressure within the chamber. In the present instance, the upper end of chamber 28 is entirely closed, and forms the movable end. The lower end is stationary, and is held to a supporting plate 29 at the central hub portion 30. This hub portion has an extension 31 which has external threads for accommodating a clamping nut 32, engaging the bottom of plate 29 and clamping this plate between it and the hub 30. The extension 31 also has an internally threaded aperture, communicating with the interior of bellows 28 and accommodating a pipe connection 33 which can be connected to the expansion space under control.

As thus far described, it is evident that upon an increase in pressure in that space, the top of bellows 28 rises; and upon a reduction in pressure, it lowers. This movement is made use of to provide a controlling function. Thus an actuator rod 34 is rigidly fastened in a vertical position in the top boss or projection 35 of chamber 28, and is slideable in a guide 36. This guide is shown in this instance as integral with a plate 37, held rigidly in spaced relation from plate 29, as by the shouldered bolts 38.

The upper end of rod 34 carries a device for operating electrical contacts. One of the important features of this invention resides in the compactness of the operating mechanism and of the contacts. For example, one set of contacts are supported by the rod 34, while the cooperating set is operated by the rod to engage the first set. For this purpose, rod 34 carries an insulation block 39, at the top end of which there are a pair of metal contact clips 40 and 41. These clips are shown most clearly in Fig. 5. They can be fastened to the sides of block 39 by the aid of the integral flat extensions 41', and screws 42. One of these screws for each clip 40, 41 can serve also to hold a lead wire 43 to the extension 41'. The wires 43 are in series with the motor circuit, and it is only when the two clips 40 and 41 are in electrical contact that the actuating motor can be energized.

The connecting devices for effecting this result include a pair of switch blades 44 and 45. These blades are supported, one on each side of an insulation support 46, to which the blades are fastened as by screws 47. The blades 44 and 45 are moreover in electrical contact, as by the aid of a wire connector

48, whereby when the blades enter between the clips 40 and 41, they serve to complete the circuit between the clips.

For permitting this blade movement, as shown in Fig. 3, a pivotal mounting for the blades is provided, as for example by the aid of a post 49, held to plate 37 by nut 50, and providing a fork at its upper end. Between the arms of the fork is pivoted a bar 51 that is screwed or otherwise fastened into the block 46.

The movement of rod 34 upwardly serves to tilt the blade assembly about the pivot of bar 51. For this purpose, blade 44 has a projection extending entirely across the block 39, and is in the path of travel of a pin 52 that is fastened in the block 39. As the rod 34 travels upwardly due to the expansion of chamber 28, blade 44 is lifted, until a central position is reached, beyond which the blades are rapidly snapped over into the position of Fig. 3. In order to accomplish this snap-over action, a spring arrangement is provided that will now be described.

As clearly shown in Fig. 2, bar 51 carries a transverse rod 53, notched adjacent each end for anchoring the tension springs 54. The other ends of the springs are similarly anchored to rods 55. These rods 55 stay stationary while the rod 53 moves in accordance with the movement of blades 44 and 45. It is evident that, as rod 34 moves upwardly from the position of Fig. 1, the first effect is a stretching of both springs 54; and this stretching continues until the axis of the springs as viewed in Fig. 2 passes through the pivot of bar 51. As soon as this central position is passed ever so slightly, the springs 54 act with a snap to complete the counterclockwise movement of blades 44 and 45.

The final result is illustrated in Fig. 3, the blades 44 and 45 engage the clips 40 and 41, and contact is made, causing operation of the compressor. Although rod 34 may continue to rise, yet blades 44 and 45 would maintain contact with clips 40 and 41, due to the tension of springs 54, exerting a resilient lifting force to these blades.

It is evident that before the springs 54 can be active to produce the snap-over action described, chamber 28 must expand to a definite size, and this in turn means that a definite limiting high pressure must be reached in the expansion space of the refrigerating system. A pair of centralizing compression springs 56 and 57 are used on rod 34, which are unflexed just at the point of snap-over. In this way, springs 54 can be made rather light, as substantially all the work they have to do is to move the blades 44 and 45. Spring 56 can be interposed between plate 37 and the projection 35 of chamber 28; while spring 57 can be interposed between guide 36 and the block 39.

It is evident that if the tension of springs 54 could be adjusted, such an adjustment would influence the amount of pressure that must be present in chamber 28 to accomplish the controlling function. When the tension is greater, a larger pressure must exist to operate the blades; and vice versa. In order to provide such an adjustment, rods 55 are movable in a direction substantially parallel to the axis of the springs, as for example, by being mounted on a nut 58. This nut, as clearly shown in Fig. 4, is arranged to traverse a thumb screw 59. This screw can be turned in one direction to move rods 55 against the tension of springs 54, or else turned in the other direction to permit the rods 55 to be pulled by the springs 54. The thumb screw 59 is kept in position by a pin 60 which extends into an aperture in the screw, and is fastened to the top of a stationary post 61. The tension of springs 54 also assist in holding the end of screw 59 tightly against this post.

The operation of opening the contacts is accomplished in a manner entirely analogous to that of closing them. The blade 44, as shown most clearly in Fig. 3, can be engaged by the head of one of the screws 42, so that when rod 34 moves downward, the blade 44 is also urged downwardly. Thus upon a sufficient contraction of the bellows chamber 28, the springs 54 are again snapped over center and the mechanism takes the position of Fig. 1. Due to the snap over action, a large current can be broken by the contacts without material danger of injurious arcing or sparking. It is also evident that an increase in tension of springs 54 by adjustment of screw 59, causes the apparatus to open the contacts only upon a lower limit of pressure being reached; that is, the pressure required to open the contacts is reduced.

In order to mount the device 26 on a base, a plurality of feet 62 can be provided on the supporting plate 29. Furthermore, I indicate a sheet metal cover 63 that can be used over the entire apparatus.

The manner of operation of this system is probably self-evident from the foregoing. When the refrigerating system is operating and the pressure is low in an expansion space, the motor is de-energized, and the compressor is idle. As soon as a definite pressure is reached, the apparatus 26 operates to close the contacts, and the compressor is set into operation. The operation continues until a definite, low pressure is reached, when the contraction of bellow chamber 28 will urge rod 34 downward to open the contacts. The cycle can then be repeated.

I claim:

1. In a pressure responsive device, a member movable in accordance with the pressure that is to operate the device, a contact carried by said member, a pivoted cooperat-

ing contact, arranged to be moved by said member in either direction, and a spring for snapping the said cooperating contact in either direction upon sufficient movement of said member.

2. In a pressure responsive device, a bellows-like container arranged to expand and contract in accordance with the variations in pressure therein, a rod attached to the movable end of said container, a contact carried by said rod, a cooperating pivoted contact arranged to be moved by said rod so as to move it toward and away from said first contact, and a spring for snapping said pivoted contact in either direction upon sufficient movement of the rod.

3. The combination as set forth in claim 2, with means for adjusting the tension of the spring, comprising a pin, a hollow screw guided on the pin, and a nut on the screw to which the spring is connected.

4. In a pressure responsive device, a bellows-like container arranged to expand and contract in accordance with the variations in pressure therein, means supporting one end of the container, a rod, attached to the other end in a direction parallel with the expanding and contracting movement of the container, a guide for the rod, a contact supported by the rod, a pivotally mounted cooperating contact structure arranged to be moved in either direction by the rod as the container expands and contracts, a spring anchored to the contact structure at a point remote from the pivot, and an anchor for the other end of the spring, located in such a place that the spring serves to snap the contact structure in either direction upon sufficient movement of the rod.

5. The combination as set forth in claim 4, with the addition of means for adjusting the pressure of the spring.

6. In combination, a movable operating member, a contact supported rigidly thereon, a pivoted cooperating contact arranged to be moved by said member in either direction, and a resilient member for snapping the said cooperating contact in either direction upon sufficient movement of said member.

7. In combination, a contact structure pivoted for movement, resilient means for snapping said structure in either direction about its pivot, and an actuator member for moving said structure, comprising a rod having a pair of spaced abutments for engaging the structure when the rod is moved, and a contact member rigidly fastened to said rod and cooperating with said contact structure.

8. In combination, a contact structure pivoted for movement, said structure including a pair of spaced blades, resilient means for snapping said structure in either direction about its pivot, a movable actuator for said structure, the spaced blades being arranged to permit said actuator to pass be-

tween them, and a pair of contact clips carried one on each side of the actuator for co-operating with said blades.

9. The combination as set forth in claim 8, with the addition of actuating pins carried by the actuator and arranged to coact with at least one of the spaced blades for moving the contact structure and for defining the limits of movement.

10. In testimony whereof I have hereunto set my hand.

WILFRED FOURNESS.
